US00D564504S

(12) **United States Design Patent** (10) **Patent No.:** **US D564,504 S**
Lyles (45) **Date of Patent:** **** Mar. 18, 2008**

(54) **SET OF BUTTONS FOR A HANDSET**

(75) Inventor: **Justin Lyles**, San Diego, CA (US)

(73) Assignee: **Nokia Corporation**, Espoo (FI)

(**) Term: **14 Years**

(21) Appl. No.: **29/278,928**

(22) Filed: **Apr. 13, 2007**

Related U.S. Application Data

(62) Division of application No. 29/231,712, filed on Jun. 9, 2005, now Pat. No. Des. 553,593.

(51) **LOC (8) Cl.** **14-03**

(52) **U.S. Cl.** **D14/247**

(58) **Field of Classification Search** D14/138, D14/147, 247-248, 341-347

See application file for complete search history.

(57) **CLAIM**

The ornamental design for a set of buttons for a handset, as shown and described.

DESCRIPTION

FIG. 1 is a front view of a set of buttons for a handset showing my new design; and,

FIG. 2 is a perspective front view thereof.

The broken line showing of the remainder of the handset is for illustrative purposes only and forms no part of the claimed design.

1 Claim, 2 Drawing Sheets
